BALLING GUN FOR ORALLY ADMINISTERING CAPSULES TO ANIMALS

Robert H. Popper, 231 Exeter Way, Hillside, N.J.

Filed Oct. 20, 1960, Ser. No. 62,552

Term of patent 14 years

(Cl. D83—12)

FIG. 1 is a top plan view of a balling gun for orally administering capsules to animals showing my new design;

FIG. 2 is a side elevational view;

FIG. 3 is a front elevational view; and

FIG. 4 is a rear elevational view thereof.

I claim:

The ornamental design for a balling gun for orally administering capsules to animals, as shown.
